UNITED STATES PATENT OFFICE.

ANDREW MUIRHEAD, OF BRADFORD, MASSACHUSETTS.

BEATING-ENGINE.

No. 909,642.

Specification of Letters Patent.

Patented Jan. 12, 1909.

Application filed September 18, 1907. Serial No. 393,484.

To all whom it may concern:

Be it known that I, ANDREW MUIRHEAD, of Bradford, county of Essex, State of Massachusetts, have invented an Improvement 5 in Beating-Engines, of which the following description, in connection with the accompanying drawings, is a specification, like characters on the drawings representing like parts.

In starting a grinding operation in an 10 ordinary horizontal pulp beater, the vat is first ordinarily partly filled with water and a certain quantity of the material to be ground is thrown into the vat. While rotation of the roll induces a circular flow about 15 the midfeather after a certain quantity of the material has been ground sufficiently to flow, yet, until this takes place, no appreciable flow is caused by the roll, the water carried under the roll being mostly lifted 20 by the blades and carried up over the roll, so that it falls back in front of it.

In the manufacture of paper box board and similar material, various forms of waste paper are extensively employed, and material of this nature is necessarily placed in 25 the vat of the beater in large bunches or bundles, which usually float on the surface of the water until they are disintegrated. Much difficulty is experienced at the beginning 30 of the operation in causing the roll to break up these bunches, so that they will pass beneath it, for the reason that there is no current to carry them in contact with the roll, and no means for holding them in contact with the roll until they become disintegrated, after they are moved in contact therewith. Furthermore, the water which is carried up over the roll tends to drive 35 these floating bunches away from the roll, as it falls back into the vat. It, therefore, has usually been necessary for the beater-tender to push the material into engagement with the roll, or hold the bunches against it until they are partly disintegrated, so that, 40 during the first part of the operation, constant pushing of these bunches under the roll is necessary in order to start and maintain the circulation. It furthermore often happens that the paddle, or implement 45 which is used in performing this operation, is caught under the roll and carried beneath it, thereby often times causing damage and necessitating shutting down the machine and raising the roll so as to remove the 50 paddle.

The object of my invention is to provide

a pulp-beater with means whereby the first part of a beating operation may be greatly facilitated, and the rapidity of circulation throughout the operation may be increased, 60 so that the time required to grind a charge may be in a large measure reduced, and further, to provide means whereby the use of a paddle, or similar implement for causing the material to pass over the bed, will not be 65 required. I accomplish this object by providing the tub of the beater with a deflecting and supporting apron which will act to enable the roll to induce a rapid flow of water to itself immediately on starting, so 70 that the bunches of material will be automatically conducted into engagement with the roll, and when once engaged by the roll, will be held in engagement therewith until they are carried over the bed plate and thus 75 disintegrated, the water falling down in front of the roll not only being prevented from impeding the movement to the roll, but even being caused to assist the feeding action. I accomplish these objects by the 80 means shown in the accompanying drawing, in which,

Figure 1 is a plan view of a beating engine provided with my invention. Fig. 2 is an enlarged sectional view on the line 85 2-2 of Fig. 1.

The form of beating engine shown is of the ordinary horizontal type in which the vat *a* is provided with the usual midfeather *b*, and a roll *c*, having a series of projecting 90 blades *c'* therein, is mounted to rotate between the midfeather and one side of the vat directly over the bed knives *d*. The usual back fall *e* is also provided and the roll rotated in the direction of the arrow in Fig. 95 2, so that the stock flows around in the vat in the direction of the arrows in Fig. 1.

According to my invention I provide, closely adjacent and beneath the intake side of the roll, a pulp supporting apron *f*, which 100 extends longitudinally from the midfeather to the side and transversely from the bottom of the vat, at a point some distance in front of the roll, upwardly and rearwardly to a point a short distance in front of a vertical tangent to the roll and then downwardly and rearwardly to the bed knives, approximately on a level with the edges thereof. Said apron is preferably constructed of a metal plate *f'*, bent transversely into the required shape, said plate 105 being provided with a solid wood support 110

beneath it. The front edge of said plate is so arranged with relation to the bottom of the vat that the surfaces thereof are practically continuous and no obstruction is presented to prevent the free flow of liquid from the bottom, onto the plate. The middle portion of the plate is convex, and its sides are reversely curved at the middle portion thereof, so that the lower portions are caved, the extent of concavity on the front side being merely sufficient to provide an easy curve up from the bottom of the vat and that at the rear side corresponding to the curvature of the particular roll in connection with which it is used, and approaching the curve of the path of the edges of the roll knives, so that the portion adjacent to its rear edge is approximately concentric to said path.

20 The convex portion of the plate on the side thereof next the roll extends rearwardly beneath the roll, approximately half the distance to the bed knives, and to within a short distance of the roll, at which point it is reversely curved to conform nearly to the curvature of the roll, and extends downwardly closely adjacent and constantly nearer thereto, so that the lower portion of the plate is approximately concentric therewith, as above stated, and a stock supporting surface is provided which declines from its highest point until it reaches the bed knives. A constantly declining, stock supporting apron is thus provided beneath and in close proximity to the roll for a distance in front thereof, from the bed knives, of fully half the radius of the roll. The bed knives may, in practice, extend slightly above the level of the plate at its lower inner end, so that the bed knives may be worn down to some extent, without having the roll blades strike the plate or apron. The depth of the tub at the highest point of the plate is somewhat greater than one-half the normal depth of the vat and preferably approximately three-fourths thereof.

In practice, the vat is ordinarily about half filled with water before starting so that the plate *f* is submerged to some depth. 50 As the roll rotates, the water in the space between the roll and the rear inclined side of the plate or portion thereof next the roll, will be rapidly drawn therefrom by the blades of the roll, causing a rapid flow over the plate and down the back side thereof to fill said space.

The rapid flow or pressure thus created will carry or force the material to the ground, which, as before stated, ordinarily floats, when first placed in the vat, over the highest part of the plate, and down between the same and the roll, until it is drawn into engagement with the knives of the roll. Sufficient pulp, or partly ground material 60 is thus lifted over the back fall within a

short time to start the circulation in the tub, which, of course, then aids in forcing the material to the roll. As there is sufficient depth of water over the highest part of the plate to float the material readily there-over, and as its surface is perfectly smooth, it in no way interferes with the free passage of the material to the roll while floating. After the material sinks, it will not lodge on the front side of the plate, as the surface 70 of the latter is practically continuous with the bottom, and the incline is gradual, so that the ordinary circulation will carry it up over the highest part.

Some of the more important functions 80 performed by the apron are to create a rapid flow of the liquid at its surface, towards and closely adjacent the front side of the roll, so that the material will be drawn rapidly thereto, even though there is no circulation in the vat, and the material may be floating some distance from the roll, and, also, to direct the bunches of material 85 against the roll knives at points some distance from the bed knives and hold them in contact therewith until they have been sufficiently torn apart to permit them to pass between the roll and bed.

As the bunches of stock are torn apart they are also positively carried down on the 95 apron until they are finally delivered onto the bed, the apron approaching the roll as the bunches are made smaller, so that it acts to hold them constantly in engagement with the roll from the time when they are first 100 engaged until they are disintegrated and carried over the bed. The apron is therefore adapted and arranged to prevent the stock from moving out of engagement with the roll after it has once been engaged, 105 thereby, as would be the case if any considerable space were provided between the roll and the bottom of the channel which leads to the bed, as is customary.

The necessity of using a paddle to hold the 110 bunches of material against the roll until they are disintegrated is therefore obviated, although, if it should become necessary to use a paddle for any purpose, as to force the bunches over the plate, it may be done 115 without risk of having the paddle caught between the roll and bed knives, the plate being disposed so as to support the end of the paddle and prevent such occurrences.

The plate does not materially reduce the 120 cubical contents of the vat, and, as it practically insures as rapid feeding of the material to the roll as is desirable, the production of the beater is materially increased, in addition to eliminating the hand labor above referred to.

The water which is carried up over the roll, and falls back into the vat in front thereof, practically all falls behind the highest portion of the plate, and thus aids in 130

driving down the material into contact with the roll, instead of driving it away therefrom.

Having thus described my invention, what I claim as new and desire to secure by Letters Patent is:—

1. In combination with the roll and bed of a pulp beater, deflecting means for conducting the stock to a substantial elevation above the level of the bed and closely adjacent the roll, at the intake side thereof, so that it will be under the feeding action of the roll blades, and a declining apron disposed to receive the stock at its upper end from said deflecting means and extending downwardly to the bed convergently with the path of the roll blades, to provide a gradually tapering space in which bunches of the stock will be held in engagement with the roll, so that they may be torn apart as they are forced down the apron to the bed, substantially as described.

2. In combination with the roll and bed of a pulp beater, an inclined stock-supporting apron at the intake side of the roll having a concaved lower portion and a convex upper portion, said apron extending upwardly from the level of the bed divergently with relation to the path of the roll blades

to a substantial elevation above the bed and beneath the roll and in sufficiently close proximity thereto to hold the stock under the feeding action of the roll-blades, and means for delivering the stock to the upper end of said apron, substantially as described.

3. A pulp beater having a stock deflecting apron extending from the bottom of the vat towards the roll, at its intake side, to a substantial elevation above the level of the bed and closely adjacent a vertical tangent to the roll, and then downwardly, and convergently with the roll, to the bed at the level thereof, the declining portion of the apron next the roll being arranged in sufficiently close proximity to the roll, adjacent its upper end, to hold the bunches of stock in engagement with the roll and to provide a gradually tapering space in which said bunches are torn apart while they are being carried down to the bed, substantially as described.

In testimony whereof, I have signed my name to this specification, in the presence of two subscribing witnesses.

ANDREW MUIRHEAD.
